(57) **CLAIM**

The ornamental design for a swirled stool, as shown.

DESCRIPTION

FIG. 1 is a center, front perspective view of a swirled stool showing my new design;

FIG. 2 is a perspective view, 30 degree rotated to the right from the center, front perspective view thereof;

FIG. 3 is a perspective view, 60 degree rotated to the right from the center, front perspective view thereof;

FIG. 4 is a perspective view, 90 degree rotated to the right from the center, front perspective view thereof;

FIG. 5 is a perspective view, 120 degree rotated to the right from the center, front perspective view thereof;

FIG. 6 is a perspective view, 150 degree rotated to the right from the center, front perspective view thereof;

FIG. 7 is a perspective view, 180 degree rotated to the right from the center, front perspective view thereof;

FIG. 8 is a perspective view, 210 degree rotated to the right from the center, front perspective view thereof;

FIG. 9 is a perspective view, 240 degree rotated to the right from the center, front perspective view thereof;

FIG. 10 is a perspective view, 270 degree rotated to the right from the center, front perspective view thereof;

FIG. 11 is a perspective view, 300 degree rotated to the right from the center, front perspective view thereof; and,

FIG. 12 is a perspective view, 330 degree rotated to the right from the center, front perspective view thereof.

This swirled stool is furniture that comprises a top surface for both seating and placing objects, and curvilinear sides that swirl around the stool to complete its unique shape.
